UNITED STATES PATENT OFFICE.

CHARLES L. HUSTON AND ALFRED GOODFELLOW, OF COATESVILLE, PENNSYLVANIA.

CLAMPING DEVICE FOR ROTARY SHEARS.

Application filed June 10, 1920. Serial No. 388,045.

To all whom it may concern:

Be it known that we, CHARLES L. HUSTON and ALFRED GOODFELLOW, citizens of the United States, and residents of Coatesville, 5 county of Chester, State of Pennsylvania, have invented certain Improvements in Clamping Devices for Rotary Shears, of which the following is a specification.

One object of our invention is to provide 10 means for holding a plate while being sheared so that it can be rotated around an axis. The invention is particularly adapted for cutting circular plates, and especially circular boiler plates.

15 A further object of the invention is to utilize a magnet for retaining the plate onto the holding means.

A still further object of the invention is to provide means for allowing the plate to 20 rotate around one or two axes.

Still another object of the invention is to provide means for holding the plate in a given position so that a true circle can be cut, and a still further object is to provide 25 means for accurately setting the plate on the magnet.

In the accompanying drawings:

Fig. 1 is a longitudinal sectional view 30 through our improved holding mechanism showing only the cutting disks of the shears;

Fig. 2 is a view illustrating the gauge;

Fig. 3 is a plan view;

Fig. 4 is a sectional view on the line 4—4, Fig. 1;

35 Fig. 5 is a sectional view on the line 5—5, Fig. 1;

Fig. 6 is a diagrammatic plan view showing the correct adjustment of the holding disk in respect to the cutters; and Fig. 7 is 40 a view illustrating the machine when sections of plates are being cut so as to obtain the full holding value of the magnetic disk.

Referring to the drawings, 1 is the frame of a shearing machine in which 2 and 3 are 45 the cutting disks. 4 is a bed plate on which is mounted a slide 5 capable of being moved towards and from the cutting disks by a feed screw 6 adapted to bearings 7 in the bed plate 4. Any suitable means may be 50 provided for turning this screw. The slide 5 has a nut 8 through which the screw extends. Mounted on the slide is a second slide 9 which is moved at right angles to the slide 5 by means of a screw 10 adapted 55 to a nut 11 on the slide. On the screw is a hand wheel 12 by which it is turned. Ar-

ranged to rotate on the slide 9 is a carrier 13 having a pivot pin 14 mounted in a center bearing on the slide 9. In order to allow it to turn freely, we provide, in the 60 present instance, a ball bearing 15. On the periphery of the carrier are teeth 16 and meshing with these teeth is a worm wheel 17 on a shaft 18 driven by a motor 18a Fig. 1. By turning the worm shaft 18, the carrier can be turned on its pivot as desired. By operating the two screws 6 and 10, the carrier can be moved into any position. Pivotedly mounted on the carrier 13 is a 65 bracket 19, which is held firmly to the carrier 13 by the pressure of a spring 20 on the pivot pin 14 which extends through an opening in the carrier as well as in the slide 9, the spring 20 being held between a nut 21 on this pin and a shoulder on the bracket. 70 The bracket may be of any length desired, depending upon the size of the machine to which the invention is applied. The bracket carries at its outer end the means for holding and supporting the disk. On the 75 bracket is an annular support 22 having a raceway in which are balls 23 and mounted on these balls is a raceway 24 having a spindle 25 held to the bracket by means of a central bolt 26 so that while the spindle can 80 turn freely on the bracket it is held in place by the bolt. Mounted on the spindle is a disk 27 carrying the magnets 28, and on the hub 29 of the spindle are terminals 30 and 31 connected to wires 32. These wires extend through the hollow spindle 14 and to any convenient point so as to connect with the wires leading from any source of electric energy. The electric wiring is merely 85 shown in diagram as this may be changed according to the design and type of the machine. We have also shown the magnets 28 in diagram.

In order to lock the raceway 24 to the raceway 22, we provide pins 33, which are 90 preferably tapered. On the bracket 19 is a projection 34 and on a suitable post 35 is a vertically adjustable bar 36, which carries an adjusting screw 37 against which the projection 34 rests when the mechanism 95 is in the cutting position so that on turning the screw the plate can be brought into correct position in respect to the cutting line. By lowering the bar 36 it will allow the bracket to swing freely. Projecting 100 from the post 35 is a bracket 38, and on the bracket 19 is a wheel 39. The post supports 105

the bracket 19 when the parts are in the cutting position.

Referring to the diagram, Fig. 6, it will be noticed that the cutting line w is at one side of the center line y of the cutting disks 2 and 3, and by adjusting the bracket by means of the set screw 37 so as to bring the center z of the magnetic holding disks 22 on the line w , the shears will cut a true circle, 10 the center z being the center of the circle. If, however, the holding disk be prevented from turning by the pins 33, then the center w is the center of rotation and this center w is the center on which the bracket 19 15 swings. When it is desired to cut a segmental plate, such as a' , shown in Fig. 7, then the bracket 19 may be shifted so that the held disk will be at one side of the center, as shown at z' , and the entire magnetic 20 surface will be used to hold the segment while the cut is being made. The dotted line a' illustrates a segmental plate on the opposite side of the center line w of the machine, supported by the holding plate when its 25 center is in the position z' .

In order to accurately locate the plates on the magnet holder prior to shearing, we mount under the disk 27, a floating ring 40 held to the disk by ring or lugs 41 secured to the disk by bolts or other fastening. In the floating ring 40 are a series of 30 holes into one of which is inserted a gauge in the form of a rod 42 on which is an adjustable finger 43, bent as shown; the rod is graduated and the finger can be held by a 35 set screw in any position desired.

The gauge and its ring can be turned and after the plate has been accurately located, the rod is removed from the ring.

40 For the purpose of moving the plate into correct position on the magnet, we provide a frame 44 pivoted at 45 to uprights on the bracket 19. The outer end of the frame 44 is attached by a link 46 to an arm 47 on 45 a shaft 48 geared to the shaft of an electric motor 49, mounted on an extension 19^a of the bracket 19. On the frame 44 are the rollers 50 spaced apart as shown in Fig. 3. When it is desired to adjust the plate, the frame is 50 raised so that the plate is supported by the edge of the disk 27 and the two rollers 50. When in this position the plate can be readily moved into true position for cutting, after which the frame is lowered and the 55 plate will rest on the disk as shown in Fig. 1.

Thus it will be seen by the above de-

scription that we are enabled to accurately locate a plate on the holder and provide means for firmly holding the plate in proper position so that when movement is imparted to the plate the cutters will cut an accurate circle and the holding device can be moved towards and from the cutters and the plate can be turned on the center z , or on the center w , as desired. 60 65

As hereinbefore stated, if a segment of a plate is to be cut then the bracket 19 is shifted so that the entire surface of the holding disk is used to support the segment 70 of the plate.

We claim:

1. The combination in plate-holding mechanism for shearing machines, of a bed located in front of the shears; a slide mounted on the bed; means for moving the slide to and from the shears; a second slide mounted on the first slide and adapted to transverse ways on the first slide; a bracket rotatably mounted solely on the second slide; a motor on said slide for turning the bracket; and a plate holding disk pivotally mounted on the slide, said disk having magnets by which the plate is held to the disk. 75 80

2. The combination in plate holding mechanism, of a support; a disk mounted on said support; magnets carried by the disk; a ring located under the disk and free to turn thereon, said ring having a series of holes; a rod adapted to any one of the holes; 85 and an adjustable finger on the rod forming a gauge. 90

3. The combination in plate holding mechanism for shearing and like machines, of a support; a magnetic holding device; and a frame having rollers arranged to engage a plate; and means for raising the frame so that the plate is supported by the rollers and the edge of the magnetic holding device. 95 100

4. The combination in plate holding mechanism for shearing and like machines, of a support, a magnetic holding device for a plate; a frame pivoted to the support; means for raising and lowering the frame; two rollers mounted on the frame, said rollers being spaced apart, and arranged to lift one side of the plate off of the holding device to allow for adjustment of said plate on the holding device. 105 110

In witness whereof we affix our signatures.

CHARLES L. HUSTON.
ALFRED GOODFELLOW.
